UNITED STATES PATENT OFFICE.

HOWARD H. DUDLEY, OF SPANISH LAKE, MISSOURI.

CHECKING OR UNCHECKING DEVICE.

SPECIFICATION forming part of Letters Patent No. 641,088, dated January 9, 1900.

Application filed May 15, 1899. Serial No. 716,973. (No model.)

To all whom it may concern:

Be it known that I, HOWARD H. DUDLEY, of the city of Spanish Lake, St. Louis county, State of Missouri, have invented certain new 5 and useful Improvements in Automatic Checkrein Attachments, of which the following is a full, clear, and exact description, reference being had to the accompanying drawings, forming a part hereof.

10 My invention relates to automatic checkrein attachments; and it consists of the novel construction, combination, and arrangement of parts hereinafter described and claimed.

Figure 1 is a plan view of a portion of a 15 harness-saddle with my improved checkrein attachment in position thereon. Fig. 2 is a longitudinal sectional view taken approximately on the line 2 2 of Fig. 1. Fig. 3 is an enlarged horizontal sectional view of the tubular casing which is secured to the harness-saddle. Fig. 4 is an enlarged sectional view 20 of the tubular casing and showing the different positions of the base of the hook in said casing. Fig. 5 is a rear end elevation of the 25 base of the hook to which the checkrein is attached.

Referring by numerals to the accompanying drawings, 1 indicates the usual harness-saddle, and upon the top of the center of said 30 saddle is fixed a tubular casing 2, with downwardly-projecting ears 3, through which pass rivets 4, the same passing through the top layer of the harness-saddle. The forward end of this casing 2 is open and provided on its 35 edge with a bead 5, and the rear end of said casing is provided with a transversely-arranged integral bar or plate 6, there being an opening 7 formed near the top and bottom edges of said plate and the top and bottom 40 portions of the rear end of said casing.

Formed integral with and projecting upwardly and rearwardly on the inside of the bottom of the casing 2 is a tongue 8.

9 indicates a leaf-spring, one end of which 45 is riveted to the plate 6, and the body of said spring passes through the rear end of the casing 2, just in front of said plate 6, there being slots 10 formed in the rear end of the casing adjacent the ends of said plate 6 for the 50 reception of said spring.

11 indicates a hook to which the checkrein is secured, which hook is provided with a cir-

cular block or base 12 on its rear end, in the front face of which block is formed an annular recess 13. Formed integral with the rear 55 end of the sides of this base 12 are ears 14, which are clamped upon the center of a doubled strap 15, the same extending rearwardly over the horse's back and to and over the dashboard of the vehicle. A short distance 60 to the rear of the point where said ears 14 clamp upon said strap the two portions of said strap are joined by a short section of leather 16. The hook 11 is provided with a suitable tongue 17, which normally closes the opening 65 into said hook and prevents the accidental dislodgment of the rear end of the checkrein.

When my improved device is in use, the rear end of the checkrein is engaged in the hook 11, as shown in Fig. 1, and the base 12 70 of the hook 11 is drawn into the casing 2 in such a manner as that the point of the tongue 8 engages in the recess 13 in the front face of said base, and in this position that portion of the spring 9 that is within the casing 2 75 engages directly against the clamping-ears 14 upon the rear face of the base 12. Said spring when in this position exerts enough pressure to retain the forward face of the base 12 against the tongue 8. Thus the checkrein 80 is held in its rearward position, and when it is desired to loosen the checkrein to allow the horse to lower his head the driver of the vehicle, without moving from the seat, manually engages the top portion of the strap 15 85 and pulls the same rearwardly. This movement necessarily compresses the spring 9 and pulls the base 12 upwardly and rearwardly into the position shown by solid lines in Fig. 4, and when in this position the point of 90 the tongue 8 is free from the annular recess 13 in the face of the said base, and a very slight forward movement of the checkrein and hook 11 allows the base 12 to pass out of the casing 2, and as the checkrein is pulled forwardly by the lowering movement of the horse's head the two parts of the strap 15 will readily slide through the openings 7. When it is desired to check up the animal's head, the driver pulls rearwardly upon the strap 15 95 until the base 12 of the hook 11 enters the casing 2, after which the lower portion of said strap 15 is pulled, which movement necessarily elevates the rear lower corner of said

base 12, and as said base 12 passes to the rear end of the casing 2 the spring 9 is compressed and the point 8 of the tongue passes into the annular recess 13. The position of the base 5 during the pulling upon the lower portion of the strap 15 is shown by dotted lines in Fig. 4.

By the use of a device of my improved construction the driver of the animal may check up or uncheck the animal's head without 10 alighting from the vehicle, and said device is simple, inexpensive, and very efficient in use.

I claim—

The improved checking and unchecking attachment, comprising the tubular casing 2 15 secured to the harness-saddle, the transverse bar or plate 6 arranged across the open rear end of said casing, the tongue 8 projecting rearwardly upon the interior of said casing, the leaf-spring 9, one end of which is riveted

to said plate 6 and the body of said spring 20 passing through slots 10 in the rear end of said casing in front of said plate, the check-rein-hook 11 provided at its rear end with the circular block or base 12, said block being recessed at 13 for engaging said tongue 25 8, means for securing a strap to the rear of said block, and a doubled strap 15, one portion of which enters said casing through an opening above said transverse bar 6 and the other portion of which enters said casing 30 through an opening beneath said bar, substantially as specified.

In testimony whereof I affix my signature in presence of two witnesses.

HOWARD H. DUDLEY.

Witnesses:

M. P. SMITH,
JOHN C. HIGDON.
